UNITED STATES PATENT OFFICE.

HAROLD VICTOR MERRETT, OF MILTON WEST, ONTARIO, CANADA.

CLOTHES TRAY.

1,414,145.

Specification of Letters Patent. Patented Apr. 25, 1922.

Application filed March 31, 1921. Serial No. 457,260.

To all whom it may concern:

Be it known that I, HAROLD VICTOR MERRETT, a subject of the King of Great Britain, and resident of the town of Milton West, in the county of Halton, in the Province of Ontario, in the Dominion of Canada, have invented certain new and useful Improvements in Clothes Trays, of which the following is a specification.

10 The invention relates to improvements in clothes trays as described in the present specification and shown in the accompanying drawings that form a part of the same.

The invention consists essentially of the 15 novel features of construction whereby a tray is provided with means for detachably supporting same from the wall of a boiler or other receptacle.

The objects of the invention are to provide 20 a convenient means for transporting wet articles from the boiler to the tubs or elsewhere, whereby the annoyance and discomfort of having to carry said articles, which are usually very hot, in the hands is eliminated, to provide a means for catching the 25 drip from said articles, and generally to provide a device of this nature which will be inexpensive to construct, efficient in operation and durable.

30 In the drawings Figure 1 is a perspective view of the device as it appears in its erected position, a portion of a boiler being shown in dotted lines.

Figure 2 is a side view of Figure 1.

35 Figure 3 is a plan view from the under side of the device.

Like numerals of reference indicate corresponding parts in the various figures.

Referring to the drawings 1 is a tray having 40 comparatively shallow enclosing walls 2 on three sides, the opposing side walls preferably converging slightly towards one another and terminating in an open end 3 adapted, when the device is erected to project over the edge of the boiler or other receptacle 4.

The tray is preferably provided with a 45 comparatively narrow strip 5 of material extending across the open end 3 and secured to the sides 2, said strip constituting a guard to prevent the articles from slipping from the tray and at the same time permitting of the draining of water from the tray.

50 6 are handles with which the tray is provided on each side thereof.

7 is a bracket comprising a metal rod bent

in substantially U shape and having its ends turned as at 8 and rotatably mounted in bearing members 9 on the under side of the tray, said bracket in its folded position projecting past the open end 3 of the tray and being adapted in the erected position of the tray to engage the wall of the receptacle on which the tray is supported.

The arms of the brace or support 7 are 65 preferably coiled backwardly on themselves intermediate of the length thereof to form oppositely disposed lugs 10 constituting stops for a brace 11 as will be described herein-after.

The brace 11 consists of a rod bent in substantially U shape and having its ends turned in substantially U shape forming intermediate portions 12 rotatably mounted in bearing members 13 from the tray bottom adjacent to the open end 3, and finger portions 14 adapted in the erected position of the tray to project over the top edge of the supporting receptacle, as shown in Figure 2 of the drawings, said brace 11 being adapted to extend 70 over the member 7 to the rear of the stops 10.

In the use of this invention the tray is suspended from the receptacle by simply drawing downwardly the free ends of the supporting brackets 7 and 11 until the end 85 of the bracket 11 engages the stops 10 on said bracket 7 and then placing the open end 3 of the tray over the wall of the receptacle with the fingers 14 extending around the edge of said wall and the end of the 90 bracket 7 resting against the side wall of the receptacle. When it is desired to transfer the articles from one receptacle to another, said articles are simply raised from the water and placed on the tray and as the 95 tray tilts slightly towards the receptacle the water from said articles will run back into said receptacle, after which the tray is detached from the receptacle by simply raising the tray by the handles 6 and tilting 100 same forwardly slightly to release the fingers 14, the wet articles may then be carried any desired distance without discomfort to the person engaged or without fear of the water from the articles escaping from 105 the tray so long as the device is carried in a slightly rearwardly tilted position.

If desirable a handle 15 or other member may be secured to the tray for the purpose of carrying or suspending same when empty.

110 What I claim is:—

1. A clothes tray comprising a tapered bot-

tom having walls extending outwardly from three sides thereof, a bracket in substantially **U** shape having its arms pivotally mounted on the underside of said bottom and adapted 5 to engage a wall of the supporting member, a bracket in substantially **U** shape pivoted adjacent to the forward end of said bottom and extending around the under side of the first mentioned bracket and carrying fingers 10 adapted to extend over the edge of said supporting member, and handles.

2. A clothes tray comprising a bottom having walls extending outwardly from three sides thereof, a bracket in substantially **U** 15 shape pivotally mounted at its ends from said bottom adjacent to the rear end thereof and adapted to engage a wall of the supporting member, a bracket supporting the first mentioned bracket and pivotally supported 20 adjacent to the ends thereof from said bottom adjacent to the forward end thereof, the ends of said second mentioned bracket being turned backwardly to form fingers adapted

to extend over the wall of said supporting member, and stops carried by said first mentioned bracket.

3. A clothes tray comprising a bottom having enclosing walls on three sides, a bracket in **U** shape pivotally supported at its ends from said bottom adjacent to the rear end 30 thereof and looped intermediate of the length thereof to form outwardly projecting stops, a bracket having right angle portions pivotally supported from said bottom adjacent to the front end thereof and extending around the under side of the first mentioned bracket to the rear of said stops and having 35 backwardly turned ends forming fingers adapted to extend over the wall of the supporting member.

Signed at the city of Toronto, this 19th day of March, 1921.

HAROLD VICTOR MERRETT.
